Edward F. Blake, deceased, late of New Haven, Conn.

Letters Patent No. 1930 Dated March 13, 1864.

Design for a Nut Cracker.

The schedule referred to in these Letters Patent and making part of the same.

Back when it may come:

Be it known that Edward F. Blake, deceased, late of New Haven in the County of New Haven and State of Connecticut, invented or produced a new and original design for a nut cracker, and I, Eli W. Blake, administrator of the estate of the said Edward F. Blake deceased, do hereby declare that the following is a full, clear and exact description of the same.

The general form of the nut cracker is designed in imitation of a crocodile or alligator with its head turned sideways at right angles or nearly so to the body. The jaws are wide open the lower jaw is stationary and secured to the base plate, while the upper jaw, which is cast in one piece with the body is movable, being pivoted by the legs a and b. The tail c. is bent so as to form a loop and thus affords a convenient hold to operate the lever. A spring d. is interposed between the base plate and the lever in rear of its fulcrum.

What is claimed as the invention of the said Edward F. Blake deceased, is, The configuration or design above described and represented in the accompanying drawing of a nut cracker.
